UNITED STATES PATENT OFFICE

HENRY LANGE, OF QUINCY, ILLINOIS, ASSIGNOR TO QUINCY STOVE MANUFACTURING CO., OF QUINCY, ILLINOIS

DESIGN FOR A GAS RANGE

Application filed October 17, 1932. Serial No. 45,380. Term of patent 14 years.

To all whom it may concern:

Be it known that I, HENRY LANGE, a citizen of the United States, and a resident of the city of Quincy, county of Adams, and State of Illinois, have invented a new, original, and ornamental Design for a Gas Range, of which the following is the specification, and reference being had to the accompanying drawing, forming a part thereof.

The figure is a perspective of the range of

my invention, illustrating the essential features of its design wherein there is provided a single dial control panel and oven control over the range oven and disposed toward the back of the range.

I claim:

The ornamental design for a gas range, as shown and described.

HENRY LANGE.
